SURVEYOR'S TARGET

Joseph E. Dobson, Lynbrook, N. Y.

Application February 21, 1955, Serial No. 34,613

Term of patent 14 years

(Cl. D52—1)

Fig. 1 is a front view of a surveyor's target showing my new design;

Fig. 2 is a rear view of the surveyor's target of Fig. 1; and

Fig. 3 is a sectional view taken along line 3—3 of Fig. 2.

I claim:

The ornamental design for a surveyor's target, substantially as shown.
